(54) **SAW MILLS**

(76) Inventor: **Thomas B. Naylor**

Thomas B. Maylor
Letters Patent

The Schedule referred to on these Letters Patent and making part of the same containing a description in the words of the said Thomas B. Maylor himself of his improvement in the Saw Mill.

It is known that I Thomas B. Maylor of Bonaville in the County of Avery and State of North Carolina have made a new and useful improvement in the Saw Mill which is described as follows reference being had to the annexed drawing of the same making part of this specification. The Saw Mill consists of a suitable frame A in which are constructed four iron posts B. Between which a gate C works up and down containing one or more saws D. To the bottom of this gate is attached a mounting rod or pitman E leading to the crank F on the longitudinal shaft G at the bottom of the frame. on this shaft is a small pulley H around which passes a belt I leading to a large pulley K and around a small pulley on its shaft passes another belt L leading to another large pulley M. To the end of the shaft of the last mentioned pulley the power is applied to operate the mill which may be water, steam, horses, or manual power. A fly wheel N is added to equalize the motion of the machine. To the gate is attached a hand or arm O which by the alternate motion of the gate is made to act upon a rag wheel P, this being forward the carriage containing the log to be sawed is upon the gate of which rag wheel is a pinion Q working into a rach R, on the under side of the carriage S. A pull T drops into the notches of the rag wheel to prevent its running. To this pull and to the hand are attached weights and U passing over a pulley V the weight resting upon a shaft W till thrown off by a trigger X acted upon by the side of one of the hand blocks Y during the advance of the carriage causing the weight to descend and thus causing the hand pull from the notches of the rag wheel. At the same moment the motion of the rag wheel is arrested by means of a governor, pulley X on its shaft around which passes a weight and a trigger, over a pulley Y at the top of the frame of sufficient strength to run the carriage back which will realize the moment the carriage reaches the end of the frame and when the hand block comes in contact with the trigger as before described. The log is caused to

Patent No.: X9700

The Head block by you says. What I claim as my invention and which I am
willing to secure by Letters Patent consists in the before described machine for sawing
timber.
